FIG. 5.

UNITED STATES PATENT OFFICE.

THOMAS LUCIEN TALIAFERRO, OF CHICAGO, ILLINOIS.

JAR-CLOSURE.

1,381,364.

Specification of Letters Patent. Patented June 14, 1921.

Application filed July 8, 1920. Serial No. 394,633.

To all whom it may concern:

Be it known that I, THOMAS L. TALIAFERRO, a citizen of the United States, residing at Chicago, in the county of Cook, State of Illinois, have invented certain new and useful Improvements in Jar-Closures, of which the following is a description, reference being had to the accompanying drawing and to the figures of reference marked thereon.

The invention relates to new and useful improvements in jar closures, and more particularly to a jar closure having spaced lugs formed thereon adapted to engage screw threads or lugs on the jar for securing the closure to the jar.

An object of the invention is to provide a closure of the above character wherein the lower edge of the flange of the closure is strengthened by infolding or bending the metal and wherein the locking lugs or projections for securing the closure to the jar are formed by horizontally indenting inwardly the strengthened lower edge so as to provide vertically extending locking lugs or projections.

In the drawings which show by way of illustration one embodiment of the invention—

Figure 1 is a side view of a closure embodying my improvements;

Fig. 2 is a bottom plan view of the same;

Fig. 3 is a view showing the blank with the depending flange and the lower edge rolled preliminary to the forming of the closure;

Fig. 4 is a view on the line 4—4 of Fig. 1 showing the completed closure; and

Fig. 5 is a similar view on the line 5—5 of Fig. 1.

My improved closure for jars is made of metal and consists of a top portion 1 having a depending flange 2. This flange is rolled or bent inwardly as indicated at 3. The rolled or curled portion 3 is formed in the first operation, made more or less open, and in the second operation is reduced to smaller proportions and the raw edge of the metal concealed between the vertical portion of the flange and the part of the flange which is turned in. The flange is then subjected to further operations which produce the curved outwardly projecting portion 4 which is provided with knurls. This curved projecting portion lies between the upper and lower

edges of the flange and is preferably close to the upper edge, and serves as a means for gripping the closure to turn the same on to or off from the jar. By curving the portion, a very much better grip may be had. The lower infolded or inturned edge of the flange is flattened as clearly shown in Fig. 4 of the drawings, so as to provide a strengthening portion 5 which extends substantially vertical. This strengthening portion 5 also hides or conceals the raw edge 6 of the metal. At four spaced points as shown in the drawings the strengthened lower edge of the flange is indented as indicated at 7 in Fig. 2. This indented portion is within the limits of the bent back portion of the metal, and the projection formed by the indenting of the flange extends horizontally inward. This produces projections or lugs which may be interlocked with suitable threads or projections on the jar for securing the closure to the jar. As clearly shown in Fig. 5 the projecting lug 7 is produced by the bodily horizontal inward displacement of the strengthened flange. The innermost portion of each lug is thus formed with a vertical face corresponding to the thickness of the lug, which vertical face is especially advantageous in that the pressure exerted against the jar for holding the closure on the jar is in a plane substantially parallel with the plane of vertical thickness.

The closure is an improvement upon the jar closure shown in the patent granted to Alfred L. Weissenthaler, February 23, 1915, Number 1,129,150, wherein the metal forming the projections extends substantially horizontally and the pressure incident to the securing of the closure to the jar is more or less at right angles to the metal and may therefore bend the projection.

I am also aware that it is old in the art to roll the edge outwardly in the forming of a closure having locking projections for holding the closure on the jar, which outward roll of the metal strengthens the edge, but in all such closures, so far as I am aware, the lugs have been formed by vertically indenting the metal at the extreme lower edge, thus forming a projection wherein the metal extends horizontally rather than vertically, as in my improved closure.

It is obvious that minor changes in the details of the shaping of the parts may be

made without departing from the spirit of the invention as set forth in the appended claims.

Having thus described the invention, what I claim as new and desire to secure by Letters-Patent, is—

1. A jar closure comprising a top portion having a depending flange formed with an outwardly projecting knurled curved portion disposed between the upper and lower edges of the flange, said flange being rolled inwardly and flattened to conceal the raw edge of the metal and strengthen the lower ends of the flange, said flange within the limits of the strengthened inturned edge being provided with spaced lugs formed by horizontally indenting the strengthened edge.
2. A jar closure comprising a top portion having a depending flange formed with an outwardly projecting knurled curved portion disposed between the upper and lower edges of the flange, said flange being rolled inwardly and flattened to conceal the raw edge of the metal and strengthen the lower edge of the flange, said flange within the

limits of the strengthened inturned edge being horizontally indented to form spaced lugs with the metal forming the lugs and adapted to hold the closure in place on the jar extending in a direction substantially parallel with the flange.

3. A jar closure comprising a top portion having a depending flange, said flange being rolled inwardly and flattened to strengthen the lower edge of the flange, said flange within the limits of the strengthened inturned edge being horizontally indented to provide spaced holding lugs.

4. A jar closure comprising a top portion having a depending flange, said flange being rolled inwardly and flattened to strengthen the lower edge of the flange, said flange within the limits of the strengthened inturned edge being horizontally indented to provide spaced holding lugs, with the metal forming the portion of the lug adapted to hold the closure on the jar extending in a direction substantially parallel with the flange.

In testimony whereof I affix my signature.

THOMAS LUCIEN TALIAFERRO.
